UNITED STATES PATENT OFFICE.

JAMES C. WOODLEY, OF EVANSTON, ILLINOIS, AND RAY P. PERRY, OF MONTCLAIR,
NEW JERSEY; SAID PERRY ASSIGNOR TO BARRETT MANUFACTURING COMPANY, A
CORPORATION OF WEST VIRGINIA.

MANUFACTURE OF COMPOSITION ROOFING-SHEETS.

1,204,632.

Specification of Letters Patent. Patented Nov. 14, 1916.

No Drawing.

Application filed December 8, 1915. Serial No. 65,687.

To all whom it may concern:

Be it known that we, JAMES C. WOODLEY, a citizen of the United States, residing in Evanston, Illinois, and RAY P. PERRY, 5 a citizen of the United States, residing in Montclair, New Jersey, have invented certain new and useful Improvements in the Manufacture of Composition Roofing-Sheets, of which the following is a specification.

Our invention aims to provide certain improvements in the manufacture of sheets for roofing and similar purposes from plastic bituminous compositions such as that described in the patent of James C. Woodley, No. 1,156,122, October 12th, 1915. This composition includes a bituminous mass with a quantity of fibers separately coated and distributed throughout the binder.

20 The plastic composition is rolled into sheets ordinarily about thirty-two inches wide and one-quarter of an inch or less in thickness, after which the sheets are wound into rolls of convenient size for handling and transportation. The rolling of the sheets compacts them in the direction of their thickness but extends their width so that when the rolls stand on end, with the weight thereof operating in the direction of the 25 width of the sheets, there is a tendency to settling, thus reducing the widths of the sheets. The customers may thus find the sheets narrower than intended, or one sheet narrower than another, or even the same 30 sheet narrower at some points than at others. The longer such a roll stands on end and the hotter the atmosphere to which it is exposed, the greater the settling, eventually reaching a maximum point at which it substantially 35 ceases.

According to our invention the coils or rolls of roofing sheets thus made are subjected to pressure in line with the axis of the rolls, that is in the direction of the width 40 of the sheet. The amount of compression which the rolls will take under these circumstances depends somewhat on the temperature. When stored in a warm room the rolls of roofing as ordinarily made and inclosed 45 in a paper wrapper may be compressed about two inches for a width of thirty-two inches. This endwise compression of the rolls serves to give an increased density to

the sheets in the direction of their width, especially at the edges where the greatest 55 strength should be. It tends also to prevent any subsequent settling of the rolls under their own weight when they stand upright for a long period prior to use. The extent to which the compression is carried 60 will vary according to composition and circumstances of storage and use. To take up all the possible shrinkage in width the rolls may be super-compressed; that is, compressed to an extent greater than the maximum which they would undergo naturally. The material is elastic and expands somewhat when the pressure is removed. Thus 65 to secure a determined ultimate width of sheet we may compress it to a less width so 70 that when it expands it will have the determined width; the extent of super-compression and of re-expansion being determinable within reasonable limits by experiment on different grades of sheets. By this compression in the factory substantial uniformity in 75 width of each sheet from end to end and in the different sheets is insured, as well as the securing of a desired width in the sheet 80 when it comes to be used.

The compacting of the composition may be effected in a variety of ways. Pressure may be applied at either end or at both ends. A short application of high pressure in this way will serve to effect practically the same 85 compression which would occur by the weight of the material itself in rolls standing on end for a long time. For example, the rolls may be enveloped in a casing and pressure applied by means of flat plates at 90 one or both ends operated by pneumatic, hydraulic, screw or other power, the pressure being applied gradually and the load being varied under different conditions. Or the rolls might be allowed to stand for a 95 sufficient length of time to settle by their own weight, pressure being applied artificially afterward to distribute evenly the reduction in width so as to secure a sheet 100 of uniform and determined width.

The sheets are made in some cases with an embossed surface. The result is that in the roll there are greater air spaces between adjoining turns in the sheet than where the sheets are made smooth. The greater the 105 air spaces in the roll the greater the possi-

ble extent of compression; and the smoother the sheets and the tighter they are wound, the less the compression permissible and desirable.

5. It is important to confine the rolls circumferentially, the endwise compression thereof being usually accompanied by a radial expansion and being restricted by any means which will prevent such expansion. Preferably the rolls are confined in a tight wrapper. This may be a strip of heavy paper or other fabric which is wound with the sheet of composition around the usual central core and which has its outer end fastened down 15 in any suitable way; or it may be a wrapper which only extends around the outside of the complete roll. Such wrapper would be left on the roll until actually used. Or a temporary casing such as a metal jacket 20 may be used only during the period of endwise compression. In either case it is important that the roll be wrapped tightly around its core, as by exerting a continuous pressure during the rolling operation at the 25 point where the sheet is tangent to the roll. This reduces to a minimum any air spaces between the successive convolutions and to a corresponding extent restricts the freedom of the material to expand radially and to 30 contract longitudinally.

What we claim is—

1. In the manufacture of sheets for roofing or the like of plastic material the method which consists in forming the material into 25 a sheet by compression in the direction of its thickness and compressing the sheet in the direction of its width while confining it in the direction of its thickness.

2. In the manufacture of sheets for roofing or the like of plastic material the method which consists in forming the material into a sheet by compression in the direction of its thickness, and increasing its density without substantial distortion by compression in 45 the direction of its width.

3. In the manufacture of sheets for roofing or the like of a composition including a bituminous mass with fibers separately coated and distributed throughout the same, 50 the method which consists in forming said composition into a sheet by compression in the direction of its thickness and compressing said sheet in the direction of its width

while confining it in the direction of its thickness.

4. In the manufacture of sheets for roofing or the like of a composition including a bituminous mass with fibers separately coated and distributed through the same, the method which consists in forming said composition into a sheet by compression in the direction of its thickness, rolling the sheet into a roll and compressing the roll in line with its axis.

5. In the manufacture of sheets for roofing or the like of plastic material the method which consists in forming the material into a sheet by compression in the direction of its thickness and compressing the sheet in the direction of its width to a width less than that to which it would naturally contract, and removing the pressure to permit partial re-expansion.

6. In the manufacture of sheets for roofing or the like of a composition including a bituminous mass with fibers separately coated and distributed through the same, the method which consists in forming said composition into a sheet by compression in the direction of its thickness, rolling the sheet into a roll and compressing the roll in line with its axis to a width less than that to which it would naturally contract, and removing the pressure to permit partial re-expansion.

7. In the manufacture of sheets for roofing or the like of plastic material the method which consists in forming the material into a sheet by compression in the direction of its thickness, rolling the sheet into a roll and confining the same radially and compressing the roll in line with its axis.

8. In the manufacture of sheets for roofing or the like of a composition including a bituminous mass with fibers separately coated and distributed throughout the same, the method which consists in forming said composition into a sheet by compression in the direction of its thickness, rolling the sheet into a roll and confining the same radially and compressing the roll in line with its axis.

In witness whereof, we have hereunto signed our names:

JAMES C. WOODLEY,
RAY P. PERRY.
